UNITED STATES PATENT OFFICE

2,092,288

PACKAGE AND CONTAINER THEREFOR

Ellsworth G. Nichols, Watertown, Mass., assignor
to E. F. Kemp, Inc., Somerville, Mass., a corpora-
tion of Massachusetts

Application April 13, 1936, Serial No. 74,162

5 Claims. (Cl. 206—44)

This invention relates to packages of confectionery or the like and it has for its object to provide an attractive and ornamental package of the class described. It is also an object of this invention to provide an improved container for holding and displaying a plurality of confectionery units each of which includes a wrapper of sheet material having end portions twisted to form ornate rosettes, one at each end of the unit, such as is shown and described in United States Patent No. 1,815,261 granted to E. F. Kemp July 21, 1931.

To these ends I have provided the ornamental and attractive package and improved container therefor, as set forth in the following description, the several novel features of the invention being separately pointed out and defined in the claims at the close thereof.

In the accompanying drawings:—

Figure 1 is a perspective view of a package of confectionery constructed in accordance with this invention.

Figure 2 is a front elevation of a package of confectionery constructed in accordance with this invention.

Figure 3 is a section on line 3—3 of Fig. 2.

Figure 4 is a plan view of an end portion of one of the partitions hereinafter referred to.

Figure 5 is a perspective view of the box element of the container forming part of the package illustrated in Figs. 1, 2, and 3.

As herein illustrated my new package includes a container comprising a box element 10 and one or more partition elements 11. The structure shown in Figs. 2 and 3 includes three of these partitions while that illustrated in Fig. 1 includes two partitions.

A plurality of confectionery units 12 are orderly arranged side by side within the box 10 in two or more layers alternating with the partitions with the topmost layer exposed to view as shown. The intermediate body portion of each unit extends transversely from side to side of the interior of the box while the twisted end portions of each unit extend through slots formed in the opposite side walls of the box so that they are disposed upon the exterior of the latter.

The box 10 is made from cardboard, or other suitable sheet material, and comprises a back or bottom wall 13, Fig. 5, two oppositely disposed end walls 14 and 15, and two oppositely disposed side walls 16, 16.

Each side wall 16 is formed with a series of approximately parallel slots 17 alternating with tongues 18, the slots of each series extending downwardly from the top edge of their wall 16

and terminating a substantial distance above the bottom wall 13 so that there is a lower portion of the side wall extending continuously from end to end thereof to reinforce and stiffen the bottom wall 13.

The partitions 11 are disposed between and alternate with the layers of units 12 and serve to divide the interior of the box into a plurality of compartments since they extend approximately from end to end thereof and are of greater width than said box.

Adjacent to each side edge of each partition is provided a row of slits or apertures 19 alternating with relatively narrow necks 20, the latter connecting the adjacent outer marginal portion 21 of the partition with the intermediate main body portion thereof. The slits or apertures 19 are spaced so that each registers with, and receives within it, one of the tongues 18. Thus each partition is removably mounted upon and interlocked with the tongues 18 of both side walls so as to serve as a connector by which said side walls are supported and held against sidewise displacement in either direction, particularly outwardly under the influence of the weight of the contents of the box. This is a distinct feature of advantage when the contents of the box is heavy and the box is being handled or transported.

Upon the outside of bottom wall 13 is fastened a collapsible leg or prop 22 which may be made from a strip of cardboard, or other suitable sheet material, and which is folded transversely upon itself as at 24, 25, 26 and 27 so that it can be disposed in a collapsed folded up condition against the bottom wall as shown in Fig. 3 or extended into operative condition to support the box so that it rests on one end and inclines rearwardly as shown in Fig. 1.

The opposite end portions of this leg or prop may be fastened to bottom wall 13 by cement or any other suitable means.

Each partition has its intermediate portion or panel formed with apertures or windows 28 through which are exposed to view the confectionery units of the layer that is below it as the units of the layer above it are dispensed.

The package made up as above described is intended for use as a counter display from which the units 12 are dispensed or sold individually, and when said units are made up with wrappers of thin sheet material having transparent intermediate portions through which the confectionery is exposed to view and with colored twisted end portions providing ornamental rosettes, as in my patent above referred to and as herein shown, the

appearance of the package is very attractive, being embellished by the variegated banks of flower-like rosettes at opposite sides of the confectionery that is exposed to view through the transparent intermediate portions of the wrappers.

What I claim is:

1. A display package comprising a box having a bottom wall, two oppositely disposed end walls and two oppositely disposed side walls, each of said side walls being made with a plurality of approximately parallel slots extending inwardly from the top edge of the wall and alternating with tongues and the slots of one side wall being disposed relatively to the slots of the other side wall so as to provide pairs of oppositely disposed slots; a plurality of layers of confectionery units within said box and parallel with the bottom wall thereof, each of said units comprising a wrapper having opposite end portions thereof twisted to form rosettes and said twisted end portions extending through a pair of said slots to the exterior of the box, and a removable partition element within said box and between said layers, said element having its opposite side marginal portions separably interlocked with said tongues so as to support said side walls.
2. A display package comprising a box having a bottom wall, two oppositely disposed end walls and two oppositely disposed side walls, each of said side walls being made with a plurality of approximately parallel slots extending inwardly from the top edge of the wall and alternating with tongues and the slots of one side wall being disposed relatively to the slots of the other side wall so as to provide pairs of oppositely disposed slots; a plurality of layers of confectionery units within said box and parallel with the bottom wall thereof, each of said units comprising a wrapper having opposite end portions thereof twisted to form rosettes and said twisted end portions extending through a pair of said slots to the exterior of the box, and a removable partition element between said layers formed adjacent to its two oppositely disposed side edges with parallel rows of apertures that are occupied by the

tongues of said side walls so that the latter are supported by said partition element.

3. A display package comprising a box having a bottom wall, two oppositely disposed end walls and two oppositely disposed side walls, each of said side walls being made with a plurality of approximately parallel slots extending inwardly from the top edge of the wall and alternating with tongues and the slots of one side wall being disposed relatively to the slots of the other side wall so as to provide pairs of oppositely disposed slots; a plurality of layers of confectionery units within said box and parallel with the bottom wall thereof, each of said units comprising a wrapper having opposite end portions thereof twisted to form rosettes and said twisted end portions extending through a pair of said slots to the exterior of the box, and a plurality of removable partition elements alternating with said layers, each of said elements being formed adjacent to its two oppositely disposed side edges with parallel rows of apertures that are occupied by the tongues of said side walls so that the latter are supported by said partition elements.

4. As a new article of manufacture, a container for confectionery units comprising a box having a bottom wall, two oppositely disposed end walls and two oppositely disposed side walls, each of said side walls being made with a plurality of approximately parallel slots extending inwardly from the top edge of the wall and alternating with tongues and the slots of one side wall being disposed relatively to the slots of the other side wall so as to provide pairs of oppositely disposed slots, and a removable partition element having its opposite side marginal portions provided with means to interlock with said tongues thereby to cause said partition element to support said side walls.

5. As a new article of manufacture, a container of the character described constructed in accordance with claim 4 and wherein the intermediate portion of said partition element that is within said box is apertured to expose the part of the contents of the box that is below said partition element.

ELLSWORTH G. NICHOLS.
